(57) CLAIM

The ornamental design for portions of an optical instrument,
as shown and described.

DESCRIPTION

FIG. 1 is a front perspective view of portions of an optical
instrument according to the invention.

FIG. 2 is a left side elevational view of the portions of the
instrument.

FIG. 3 is a rear elevational view of the portions of the
instrument.

FIG. 4 is a front elevational view of the portions of the
instrument.

FIG. 5 is a top plan view of the portions of the instrument;
and,

FIG. 6 is a bottom plan view of the portions of the instru-
ment.

In the above drawings, any portions shown in broken lines
do not form a part of the invention. In addition, any views
not shown thereof do not form a part of the invention.
